SECTIONAL BRUSH

Edmundo Cortes, New York, N. Y.

Application December 19, 1947, Serial No. 792,703

1 Claim. (Cl. 15—202)

1

The present invention relates to improvements in brushes and, more specifically, to a brush for painters, enamelers, varnishers and the like, with which in an economic and simple manner a complete painting job can be done with the use of a single brush. For painting, enameling, or varnishing a house or furniture, a painter needs an expensive set of brushes, which if not in use constantly deteriorates, so that its useful period of life is reduced.

It is practically impossible for a painter to clean thoroughly a brush which is going to be used for a few hours later during the same day.

For the painting of walls and ceilings usually a brush of 6" in width is used; for the woodwork a brush 5" or 4" is used; for trimming a brush 3" or 2"; then for painting small parts and for retouching a 1" brush is needed. From this set of brushes only the brush 1" can be cleaned and used the same day, because it is easy to remove the solvent used for removing the oil and pigment from this small brush. From a bigger brush it is impossible to remove the solvent, mostly it is left to evaporate overnight. A brush soggy with solvent spreads a thin film of paint which tends to run, and also the solvent keeps dripping for a long time, injuring other surfaces which were painted or are going to be painted. A painting job done with a brush which contains solvent, in a few months shows that the painter had no skill in his art, because the paint peels or cracks. If the brush is put aside without cleaning, in one or two hours the bristles become stiff and fragile and break at the points where the pressure requiring flexibility is exerted.

Another reason for the destruction of a brush is the accumulation of pigment at the base of the bristles, which is removed only in part at the cost of a few hours labor and by the application of strong solvents which slowly kill the flexibility of the bristles.

Moreover, the rapid destruction of a brush also results from the fact that the frontal and lateral bristles are subjected to almost all the friction and wear out more quickly than those at the center rows.

Therefore, one object of the present invention is the provision of a sectional brush consisting of narrow sections more or fewer of which can be attached to one another for the purpose of enlarging or reducing the width of the brush; sections which are not in use temporarily can be kept in a solvent in order to avoid the bristles becoming stiff and the pigment set at the base of them. Said sections are of a small size, so that

2

with the help of a paper or rag all solvent easily can be removed thus avoiding dripping and dilution of the material used for painting.

Another object of the present invention is the provision of a sectional brush whose sections can be interchanged easily with one another and without the application of any considerable amount of skill, so that a constant excessive wear of one and the same bristles at the end portions of the brush will be avoided.

Still another object of the present invention is the provision of a sectional brush which, although it is only one unit, will substitute an entire set of separate brushes of different length and width, thus greatly reducing the expenses for painting and varnishing equipment.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawing the preferred forms of the invention have been shown.

In said drawing:

Figure 1 is a front elevation of a preferred embodiment of my invention;

Fig. 2 is a side elevation of the same;

Fig. 3 is a front elevation of a modification; and

Fig. 4 is a side elevation of the modification of Fig. 3.

The numeral 1 denotes a center brush head section having flat, parallel sides and being provided with bores which are extended therethrough at right angles to said flat sides. A handle portion 7 extends from the upper extremity of the section 1 and preferably is made as a unit therewith as in the instance shown, and bristles 8 are attached to the lower portion of the section 1, so that the latter represents a complete narrow brush, for instance a brush of one inch in width. Attached to both flat opposite parallel sides of the section 1 are a plurality of lateral brush sections. In the present instance there are ten sections 2, 2', 3, 3', 4, 4', 5, 5', 6 and 6'. These lateral sections, which also are provided with bristles 8, are detachably connected to one another and to the center section 1 by any suitable means, for instance by means of a pair of bolts 10 and nuts 11. The bolts 10 are extended through bores in the lateral sections 2 to 6 and

2' to 6' inclusive. Said bores register with the bores in the center section 1.

With this arrangement it is easy to interchange the various lateral sections with one another. For instance, the sections 6 and 6' can be interchanged with the sections 2 and 2', and the sections 5 and 5' can be interchanged with the sections 3 and 3', so that the bristles of the outer sections are not subjected constantly to excessive wear.

Also the width of the brush can be changed easily by attaching more or fewer lateral sections to the center section. Bolts of different length preferably are used in connection with variations of the number of lateral sections attached to the center section 1.

Since the bristles 8 are made of a uniform length, which is just the right length for the largest possible brush width attainable with this device, it is desirable to reduce the effective length of the bristles in correspondence with a reduction of the width of the brush. I prefer to carry out this feature of my invention in the manner shown in Figs. 3 and 4, where it will be seen that a clamp 12 is used for this purpose. In Fig. 3 only four lateral sections 2, 2', 3 and 3' are attached to the center section 1 by means of short bolts 20 and nuts 11. The clamp 12 consists of any suitable resilient material, such as sheet steel, plastic material, or the like. It has a perforation 15 in its back 14 for extending therethrough the handle 7. A pair of blade portions 16 and 17 are adapted to press with their lower extremities laterally in opposite direction against the bristles 8, thus reducing the effective length of the bristles 8 to that portion of them which protrudes beyond the lower extremities of the blade portions 16 and 17, as shown in Fig. 4. Lateral overlapping tongue sections 18 and 19 may be extended rectangularly from the blade portions 16 and 17, in order to prevent a side-wise dislocation of the bristles 8. For each width of the brush, or for each pair of lateral sections, and for the center section 1, preferably one clamp 12 is furnished with the device.

Since certain changes may be made in the above article and different embodiments of the invention could be made without departing from the scope thereof, it is intended that all matter contained in the above description or shown in

the accompanying drawing shall be interpreted as illustrative and not in a limited sense.

It is also to be understood that the following claim is intended to cover all of the generic and specific features of the invention herein described, and all statements of the scope of the invention which as a matter of language might be said to fall therebetween.

Having thus fully described my said invention, 10 what I claim as new and desire to secure by Letters Patent in the United States is:

A sectional brush comprising a brush head center section provided with a handle and bristles and having flat side portions from which a pair of reinforced bores are extended through the brush head center section, a plurality of lateral brush sections each of which consists of a narrow brush head with bristles thereon and having flat side portions and being provided with a pair of reinforced bores which register with the bores in said center section, a bolt provided with a nut being extended through each row of registering bores in said sections for detachably connecting said lateral sections to one another and to said center section, and a U-shaped clamp consisting of a perforated back portion and a pair of resilient blade portions extending downwardly from said back portion and being slipped over the brush, thereby the handle being extended through the perforation in the back portion of the clamp while the lower sections of said blade portions press upon the bristles in opposite lateral direction.
